(57) **CLAIM**

The ornamental design for a handle of a conducted electrical weapon, as shown and described.

DESCRIPTION

FIG. 1 is a front, top and left side perspective view of a handle of a conducted electrical weapon;

FIG. 2 is a bottom, rear and left side perspective view thereof;

FIG. 3 is a front elevation view thereof;

FIG. 4 is a rear view thereof;

FIG. 5 is a right side elevation view thereof;

FIG. 6 is a left side elevation view thereof;

FIG. 7 is a top plan view thereof; and,

FIG. 8 is a bottom plan view thereof.

The dashed lines in the drawing show structure of the environment of the handle and form no part of the claimed design.
